UNITED STATES PATENT OFFICE.

GIUSEPPE POLVERINO, OF NEW YORK, N. Y.

PICTURE-HOLDER.

1,104,219.

Specification of Letters Patent. Patented July 21, 1914.

Application filed October 9, 1913. Serial No. 794,303.

To all whom it may concern:

Be it known that I, GIUSEPPE POLVERINO, a citizen of the United States, residing at New York, in the county of New York and State of New York, have invented certain new and useful Improvements in Picture-Holders; and I do declare the following to be a full, clear, and exact description of the invention, such as will enable others skilled in the art to which it appertains to make and use the same.

This invention relates to picture frames and more particularly to the means for holding pictures therein.

The object of the invention is to provide a simply constructed and efficient device for enabling the quick removal and insertion of a picture, the glass in front thereof, and the backing therefor.

With this and other objects in view, the invention consists of certain novel features of construction, and the combination and arrangement of parts, as will be more fully described and claimed.

In the accompanying drawings:—Figure 1 represents a rear view of a frame equipped with this improved holder, in closed position. Fig. 2 is a longitudinal sectional view taken on line 2—2 of Fig. 1. Fig. 3 is a similar view showing the holder swung outwardly. Fig. 4 is a detail sectional view.

In the embodiment illustrated, a frame 1 is shown constructed in the usual manner of side and end rails having mitered corners.

2. The end and side rails of the frame have their rear edges cut out to form a seat 3 of sufficient depth to receive the picture holder, which constitutes this invention.

This holder comprises a frame 5 shaped to fit within the seat 3 and composed of side strips 6 and 7 and an end strip 8, each having parallel inturned flanges 9 and 10, between which the picture, its protective glass, and its backing are designed to fit. The inner flanges 9 of the side members 6 and 7 are connected at their free ends by an end strip 11 which is disposed in position to rest on the end of the seat 3, whereby this end of the holder is left open to permit a picture to be slipped into the holder. The outer flanges 10 of the side members 6 and 7 are cut away at this end of the holder to provide for the attachment of a securing member 12 which is hingedly connected with the side strips 6 and 7 at a point spaced from the ends thereof, and shuts down over

the ends of said strips forming a closure for the holder, to prevent longitudinal movement of the picture, its backing, and protective glass after they have been inserted in operative position. This closure comprises two side strips 13 and 14 connected at one end by an end strip 15, on which latter is mounted a spring catch 16. One edge of the side and end strips of this closure has an inturned flange 17 a portion of said flange on the side strips 13 and 14 being cut away at the free ends of said strips as shown at 18, said ends being pivoted to the side strips 6 and 7, and the terminals of the flange 17 abut against the flanges 10 of the side members 6 and 7 when said closure is in closed operative position. The flanged end strip at the other end of the holder is hingedly connected to one end of the frame by any suitable means, the hinges here shown being in the form of tongues 19 which extend through slits in the end strip 8 being held against separation from said strip by means of pintles 20 which extend across the slits in the end strip 8. If desired this holder 5 may have a cross bar 21 arranged intermediately of its ends on its outer face for the attachment thereto of a support 22 which is preferably pivotally connected with said cross bar and is designed to support the frame in upright position when desired. A catch plate 23 is shown secured to one end of the frame and is designed to coöperate with the spring catch 16 carried by the securing member 12.

When it is desired to insert a picture in the holder, the catch 16 is disengaged from the plate 23, the holder being then swung outwardly from the seat 3. When in this position, the protective glass, the picture and its backing may be slipped into the holder through the open end, and said securing member 12 is then shut down over said end, and the holder swung inwardly into the seat 3, the catch engaging the plate 23 and securely holding it in operative position.

I claim as my invention:—

A picture holder comprising side members 105 having laterally spaced inturned flanges, a flanged end member connecting said side members at one end, a strip secured to one of the flanges on each side member at the other end of said side members, the other flanges 110 on said side members being cut away at this strip connected end, and a closure for

said end comprising side and end strips each having an inturned flange on its outer edge, the ends of said side strips being connected to the side strips of the holder proper and having their flanges cut away for a portion of their length.

In testimony whereof I have hereunto set

my hand in presence of two subscribing witnesses.

GIUSEPPE POLVERINO.
